UNITED STATES PATENT OFFICE.

LEON BAZAINE, OF ISSY-LES-MOULINEAUX, FRANCE.

HYDROPLANE.

1,125,794.

Specification of Letters Patent. Patented Jan. 19, 1915.

Application filed November 18, 1914. Serial No. 872,833.

To all whom it may concern:

Be it known that I, LÉON BAZAINE, a citizen of the French Republic, residing at Issy-les-Moulineaux, Seine, France, have invented certain new and useful Improvements in Hydroplanes, of which the following is a specification.

This invention relates to hydroplanes or gliding boats with aerial propeller.

10 The invention comprises the combination with a central hull carrying the engine, the tank, the steering apparatus, the seats for the drivers and passengers etc., of two detachable lateral floats carrying sustaining bodies of variable inclination, which, when the apparatus is traveling at full speed are alone exposed to the dynamic reactions, the central hull being then out of the water. The inclinations of the sustaining bodies can 15 be controlled independently or collectively for balancing and steering purposes.

In the accompanying drawing given by way of example, Figure 1 shows a longitudinal elevation of a construction of a hydroplane according to this invention; Fig. 2 is a corresponding view in plan; and Fig. 3 is a front elevation of the apparatus. Fig. 4 is an enlarged detail elevational view of one of the hand wheels,

30 As shown in the drawing, the apparatus is chiefly constituted by a hull *a* having any suitable shape, but which, in the example illustrated, is of rectangular shape and rounded off in front. The bottom is flat or 35 may be serrated or corrugated, and raised in front. This hull, which may be made of wood or metal, comprises a certain number of water-tight chambers. It insures the floating of the whole apparatus. The hull 40 is combined with lateral floats *b*, the arrangement and number of which may be any desired. These floats may be of any known type, and they are connected to the hull *a* by means of suitable shock absorbers or 45 springs. The floats are, however, preferably constructed as follows:—Each float is formed of two lateral girders *c* firmly connected together, in the interior of which can move bodies *d* forming sustaining "planes" or 50 surfaces, and having for instance the shape of wedges and movable about a transverse axis *e* arranged at their front edge. The movement of the wedges *d*, and consequently 55 their inclination relatively to the body of the float *b*, can be regulated and controlled

by any desired gear, for instance by means of a screw *f* and hand wheel *g*. In this way, any suitable inclination can be given to the lower portion of the wedges *d*, the surface of which may be flat or suitably curved. 60 The wedges thus form projections from the floats. Springs or other shock-absorbers may be inserted between the wedges *d*, and the frame or the control members for the purpose of absorbing shocks. The number of 65 the planes or wedges *d*, as well as their volume and respective dimensions, depend on the qualities to be obtained. Care must be however taken to have a sufficient number, so that the contact surfaces should have the 70 tendency to become continuous, which reduces shocks.

In the construction illustrated, each float *b* has three pivoted planes *d* which, under the dynamic reactions, raise the hull *a* out 75 of water when the apparatus is traveling at full speed. The working and the efficiency depend on the submerged surfaces and on their inclination (apart from the resistance of the air which is constant for a given 80 speed).

By means of the hand wheels *g* or like regulating parts, the dimensions and the respective positions of the planes *d* relatively to the water level being given, it is possible 85 to vary the extent of the surfaces and the inclinations, which consequently modifies the working of the apparatus. It is thereby possible to insure the highest possible efficiency, and consequently speed, which could 90 not be obtained with planes of a constant inclination. This possibility of independent regulation of each of the planes *d* makes it finally possible to obtain perfect balancing, the inclined plane being considered as 95 a wing of an aeroplane. It is possible to mount the planes *d* on springs arranged for instance between their upper faces and the bottom of the float *b* supporting them. In this way the variable factors, that is to say, 100 the surface and the inclination, fluctuate about the said best values. It will be seen that when the speed increases, if the springs are arranged behind the axis of rotation *e*, the dynamic pressure on each plane *d*, 105 which is equal to $R - KSV^2$, will remain constant as it balances the same fraction of the weight. Consequently the speed can increase without the gliding boat having the tendency to come out of the 110

water, which is possible in other constructions and which, in combination with bad balancing, produces shocks which are exceedingly dangerous in apparatus of this kind. Owing to the means described, surfaces are therefore obtained which work like spring-controlled wings, or wings with variable inclination, of certain aeroplanes.

From the point of view of construction proper, the planes *d* may be made of wood with sheet metal bottoms ribbed inside. They are preferably filled with kapok or other swelling material. They may therefore burst or leak without this being in any way dangerous, so that, since they are alone exposed to shocks—as when traveling at full speed, the central hull rises out of the water—the buoyancy of the apparatus is not endangered. Moreover, owing to the construction adopted, it is possible to remove quickly a damaged wedge for the purpose of replacing it by another.

It is obvious that instead of using wedges *d*, it would be possible to use ordinary planes coincident with their lower surface, but in that case the water passing above the planes, plays an injurious part more particularly at low and medium speeds.

Such a gliding apparatus can be steered like any ship by means of vertical rudders *k*, but the arrangement according to this invention has a further advantage of providing for turning or rotating by differential control of the inclination of the planes *d*. It is sufficient in that case to connect the hand wheels *g* by any suitable gear. The movements to be effected in the latter case are similar to the manipulation of warping or to the manipulation of surfaces playing a similar part in aeroplanes, and produce the same phenomena.

The floats *b*, such as described, are more particularly suitable for a hydroplane. It would be sufficient simply to give them a sufficient volume by making them in the form of a water-tight chamber, under the bottom and between lateral sides of which would be pivoted the planes or wedges *d*,

the whole of which form projections from the float.

The main feature of the gliding apparatus described is that the members taking up the dynamic reactions, at high speeds, are numerous bodies *d* of small capacity, the inclinations of which are variable. These variations in the relative inclinations are either determined beforehand or can be modified while traveling at the will of the pilot, for the purpose of insuring the balancing and the steering of the apparatus in the same way as in an aeroplane.

What I claim as my invention and desire to secure by Letters Patent is:—

1. In a hydroplane, a hull, a motor and aerial propeller for driving the hull, a plurality of floats attached laterally to the hull, transverse axes arranged in the floats, wedge shaped sustaining bodies pivoted at their apices on the transverse axes and arranged within the floats with their sustaining surfaces projecting downwardly from the floats, shock absorbing means for the sustaining bodies, screws adapted to adjust the inclinations of the sustaining bodies, and control gear for operating the screws individually and collectively.

2. In a hydroplane, a floating hull, watertight compartments in the hull, a motor and aerial propeller for driving the hull, a plurality of floats attached laterally to the hull, transverse axes arranged in the floats, wedge shaped sustaining bodies pivoted at their apices on the transverse axes and arranged within the floats with their sustaining surfaces projecting downwardly from the floats, and means for varying the inclinations of the sustaining surfaces relatively to the water line and to each other.

In testimony whereof I have signed my name to this specification in the presence of two subscribing witnesses.

LÉON BAZAINE.
